United States Patent Office

Des. 198,082
Patented Apr. 28, 1964

198,082

TEACHING MACHINE

Phillip L. Ward, 220 Shadowood Lane, Northbrook, Ill.,
and Warren H. Ward, Jr., 2963 Payne, Evanston, Ill.

Filed Dec. 26, 1963, Ser. No. 77,935

Term of patent 14 years

(Cl. D25—1)

Des. 198,082

PAGE 2

FIG. 1 is a perspective view of the teaching machine embodying our new design;

FIG. 2 is a side elevational view as seen from the right-hand side of FIG. 1;

FIG. 3 is a side elevational view as seen from the left-hand side of FIG. 1;

FIG. 4 is a top plan view;

FIG. 5 is a front end elevational view as seen from the left side in FIG. 2 and from the bottom in FIG. 4;

FIG. 6 is a bottom plan view; and

FIG. 7 is a rear elevational view.

We claim:

The ornamental design for a teaching machine, substantially as shown.
